ATTORNEYS.

Patented Dec. 27, 1927.

UNITED STATES PATENT OFFICE.

TAYLOR MATSON, OF PHILADELPHIA, PENNSYLVANIA.

BOILER.

Application filed June 15, 1921. Serial No. 477,638.

My invention consists of a furnace having a fire brick base structure, the bricks of which appear on the exterior thereof where they are removable, an additional combustion chamber formed of opposed water legs, and fuel flues on said structure, said flues forming separate heating elements for said legs, and communicating vertical passages connecting said flues forming pluralities of fuel receiving flues and an upper chamber adapted to receive the products of combustion from said flues, said flues serving to subject the water legs to increased heating actions.

It consists also of a baffle plate in said heat receiving chamber adapted to cause the ascending products of combustion to be deflected downwardly in said chamber to the place of exit therefrom, thus heating a water jacket on said upper chamber.

It consists also of a perforated plate which may be lowered in the heat receiving chamber to act to dampen the fire and when not required may be raised and supported on the aforesaid baffle plate.

It consists also in forming the fire brick structure of separate bricks placed side by side and in tiers one above the other without mortar or cement between their joints so that air may pass through said joints into the fire pot and so supply the latter therewith.

The invention is satisfactorily illustrated in the accompanying drawing, but the important instrumentalities thereof may be varied, and so it is to be understood that the invention is not limited to the specific details shown and described, as long as they are within the spirit or scope of the claim.

Fig. 1, represents a partial vertical section and partial front elevation of a furnace embodying my invention.

Fig. 2, represents a horizontal section thereof on line 2—2 of Fig. 1.

Fig. 3, represents a horizontal section of a portion on line 3—3 of Fig. 1.

Fig. 4, represents a vertical section showing the fuel inlet and the door therefor.

Similar numerals of reference indicate corresponding parts.

Referring to the drawings:

1 designates the fire pot of a furnace, the same being composed of a fire brick structure formed of fire bricks 2 placed side by side and imposed in series of tiers one on top of the other and appearing on the exte-

rior of the fire pot they being clamped between the upper and lower plates 3 which are tightened by the bolts 4, the structure being supported on the ash pit 5. 6 is the air supply door and 7 its supporting frame.

Supported on the upper clamping plate 3 of the fire pot structure are the inturned water holding sections 8 whose inner terminal walls are separated forming the vertical flues or passages 9. The legs are formed of opposite half sections each of which is connected with the side walls 10 provided with flanges 11 through which are passed the bolts 11 whereby said walls and consequently said water legs may be connected and clamped firmly together.

The walls 10 are set out from the adjacent side walls of the water legs 8 providing water receiving passages 12 which are in communication with the interior of said legs and so have the water circulate through said legs and passages.

The inner side walls of said legs 8 converge from the outer walls thereof to the centres of said legs where they join the walls of the passages 9 between adjacent legs forming a series of fuel receiving flues 13, adjacent flues being in communication by said passages 9 as most plainly shown in Fig. 2. Said flues are open at the top whereby fuel may be directed into the same. They are also open at the bottom and so placed in communication with the fire pot. Owing to the converging nature of the side walls of the flues 13 they produce large heating surfaces for the water surrounding the flues.

The legs are provided with suitable intakes 14 for supplying the legs with water. The flues 13 and passages 9 form also combustion chambers which are supplied with fuel at the open tops of said flues, fuel also descending and entering the fire pot below by which means the water legs are further subjected to the heat from said flues thus highly heating said legs and consequently producing large volumes of hot water.

Superimposed on the flues 13 is the chamber 15 which is adapted to receive the products of combustion from said flues, the bottom of said chamber having therein the opening at 16 which may be covered in part by the swinging perforated damper 17 which being hinged to the adjacent portion of the lower end of the chamber 15 may be lowered over said opening and so serve by its perforations as a damper for the fire when so re-

quired. The damper 17 may be raised clear of said opening and then held in elevated position by the catch 18 on the upper limb of the imperforated baffle plate 19 whose lower end is secured to the adjacent portion of the chamber 15, said plate then rising from said portion to nearly the top of the chamber leaving a passage or space for the products of combustion as shown by the large arrow, 5 Figure 1. The upper limb of the baffle plate is secured to the top of the chamber 15 by the bolt 20. The catch 18 is hinged to the top limb of the baffle plate 19 and its nose portion is adapted to engage the adjacent 10 edge of the damper 17 and so hold the latter in elevated position. When the catch is properly drawn from the damper the latter is released and so may be lowered over the opening 16 for the purpose hereinbefore referred to.

It will be noticed that the chamber 15 is formed of an independent section or a section separate from the sections of the water legs 8 and fuel flues 13. In the side wall of 25 the chamber is the fuel inlet 21 which is provided with the door 22 which is provided with the damper 23, the latter when not required to be opened being adapted to be closed by the cap 24 which is removably 30 fitted on the wall of said damper.

In the side of the chamber is an opening occupied by the collar 25 for the exit of the products of combustion and the attachment thereto of the smoke pipe or flue 26. The 35 wall of the chamber 15 is surrounded by the water jacket 27. The exit of the hot water may be as at 14^x.

The fuel is supplied through the inlet 21 and so enters the flues 13, the passages 9 and 40 the fire pot in the brick structure, the fuel burning from the latter through said passages 9 and flues 13 and the products of combustion then being directed to the passage or space at the top of the baffle plate 19 the latter being inclined inwardly from one side of 45 the bottom of the chamber 15 to the opposite

side thus uncovering the exit collar 25 of the exit flue 26 which directs the products of combustion to the atmosphere.

Should it be desirable to dampen the fire 50 the door 22 is opened rendering the catch 18 accessible. The catch is then operated to release the damper 17 when the latter then drops or lowers on the base of the chamber 15 over the opening 16 therein, when the 55 products of combustion from the flues 13 pass through the perforations or openings in the damper. The bricks 3 are placed side by side and on each other without mortar or cement and so admit air to pass between the 60 joints thereof and so enter the fire pot formed by the brick structure.

When the bolts 4 are displaced the fire bricks may be removed from the exterior of the furnace by being withdrawn outwardly 65 therefrom.

I claim:

In a boiler, an ash-pit, a horizontally arranged frame superimposed thereon and secured thereto, fire bricks superimposed upon 70 said frame and upon one another in staggered order to provide a fire pot for the admission of air between said bricks, a second horizontally arranged frame mounted upon said bricks, bolts arranged vertically for connecting said horizontal frames together, a hollow, vertically arranged, rectilinear structure in two vertically divided parts provided internally with opposed, vertical, corrugated sections arranged above and supported by 75 said fire pot, a second rectilinear section superimposed upon said first rectilinear structure, a firing door carried upon said second section, a baffle arranged above and in said second section, and a perforated damper 80 secured to said baffle and adapted to be lowered into a horizontal position above said first mentioned section and in a plane substantially below the opening as closed by said firing door.

TAYLOR MATSON.
